ABSTRACT: An arrangement for the rotor of a rotary regenerative heat exchanger whereby a highly effective heat absorbent element thereof is arranged in axially spaced layers closely adjacent opposite ends of the rotor. By this arrangement a pressurized cleaning fluid such as water, steam or air projected on to the element at the ends of the rotor does not lose any significant portion of its energy while being projected between the nozzle and the element. Foreign deposits on the surface of the element accordingly receive near maximum shock effect from the cleaning fluid and are thus effectively removed from the element so that a clean element may be maintained.

ROTARY REGENERATOR CLEANING ARRANGEMENT

BACKGROUND OF THE INVENTION

In rotary regenerative heat exchange apparatus a mass of heat exchange material commonly comprised of packed element plates is positioned in a hot gas passageway to absorb heat from the hot gases passing therethrough. As the plates become heated in the hot gas stream they are moved into a spaced gas passageway where the heated plates transmit their heat to cooler air or other gases passing therethrough.

As the hot exhaust gases pass through the heat exchanger, soot and fly ash are deposited on the surfaces of the heat transfer plates. Depending upon the temperature and other characteristics of the exhaust gases traversing the heat exchanger, maximum deposits usually accumulate at the "hot" end or at the "cold" end of the rotor, that is, at the end of the rotor adjacent the inlet for hot gas or at the opposite end adjacent the inlet for cool air. Should significant deposits accumulate, the operational effectiveness of the heat exchanger may be seriously curtailed.

Various arrangements have been adapted to remove these deposits from the plates by subjecting the deposits thereon to a spray of cleaning fluid such as water, steam or air whereby the energy of the cleaning fluid is effective in dislodging the deposits and leaving a clean mass of element having maximum heat transfer effectiveness and minimum resistance to flow.

The projection of cleaning fluid upon the element in the rotor compartments is usually effected by means of a nozzle carried by the housing adjacent the end of the rotor having maximum deposits thereon. Inasmuch as design requirements of the rotor necessitate placing the cleaning nozzle a significant distance from the end of the rotor, a substantial portion of the energy of the cleaning fluid is usually dissipated after it leaves the cleaning nozzle and before it reaches the element surface to be cleaned.

This invention is accordingly directed to an arrangement for a rotary regenerative heat exchanger in which the element of a highly effective form is supported outward from the end of the rotor directly adjacent the outlet of the nozzle for the cleaning fluid and in the space through which the cleaning fluid must usually be projected before it reaches the element on which the deposits are collecting.

SUMMARY OF THE INVENTION

This invention therefore relates to a rotary regenerative heat exchanger and to a particular arrangement by which the heat absorbent element thereof may be supported in the space closely adjacent the outlet from the nozzle for cleaning fluid. By this arrangement cleaning fluid exhausted from the nozzle is projected directly onto the deposits of the heat absorbent element before it loses a significant portion of its energy in traversing the space therebetween.

BRIEF DESCRIPTION OF THE DRAWING

FIG. 1 is a cross section of a rotary regenerative heat exchanger embodying the invention.

FIG. 2 is an enlarged cross-sectional view showing the details of the divided rotor comprising the invention.

FIG. 3 is a cross-sectional view of a circumferential seal on a rotor according to the invention, and

FIG. 4 is a cross-sectional view of a rotary regenerative heat exchanger constructed in accordance with conventional design.

As illustrated in the drawing the heat exchange apparatus comprises essentially a housing 10 enclosing a rotor 12 containing a mass of heat exchange material 14 that is contacted by a stream of hot gases entering the housing through an inlet duct 16 and being exhausted through an outlet duct 18 after having traversed the heat exchange material in the compartments therebetween. Cool air or other gas entering the housing through an inlet 22 is exhausted through an outlet duct 24 after having traversed the heat exchange material lying in the compartments therebetween. While the gases are being

directed through their respective passageways the rotor 12 is being rotated about its axis by drive means 20 in order that each portion of heat exchange element contained therein may be alternately subjected to the hot gas and cooler air.

5 The heat exchange material carried by the rotor usually comprises a mass of heat absorbent plates formed with projections that provide flow passageways therebetween for the flow of hot and cooler gas. The projections on the plates usually are of such size that they space the plates sufficiently far apart whereby contaminants in the gas stream do not collect upon the surface thereof in such amounts as to interfere with the normal flow of fluid. Occasionally, however, deposits on the plates do interfere with the regular flow of fluid, and cleaning means, in the form of a cleaning nozzle 26 on a pivotal cleaning arm direct a pressurized fluid such as air, steam or water on to the heat absorbent plates to remove the deposit collections therefrom and return them to their original clean condition.

20 Highly effective "laminar" heat exchange element has been developed wherein an amount of such element has the equivalent heat exchange effectiveness of a much greater amount of conventional element. If the more effective laminar-type element is placed in the rotor of a conventional heat exchanger, only a portion of the space occupied by the original element is required to provide an equivalent heat transfer capacity. Therefore a rotor designed for the use of "conventional" element therein finds but a fraction of the allotted space required for the utilization of laminar-type element.

25 Inasmuch as a stated volume of "laminar" element is equal in effectiveness to that of a much larger volume of conventional element, replacement of conventional element with an equivalent amount of that of the laminar-type will result in a rotor having a void space therein. The element is accordingly arranged in spaced layers at the "hot" and "cold" ends of the rotor with "void" therebetween in the manner shown by FIG. 2. This arrangement thus provides for several independent blocks of element, each of which is relatively small and may be handled with comparative ease.

30 To facilitate mounting each element block 36 within each sector shaped compartment of the rotor, special L-shaped brackets 30 are positioned radially between the central rotor post and the rotor shell 10 and secured by bolts 32 to axially opposite ends of each radial partition 34. The brackets 30 in each compartment face inwardly in order that the horizontal arms thereof may provide supports on which the sides of the element blocks may securely rest during normal operation of the rotor.

35 The same bolts 32 that secure the brackets 30 to the radial partitions 34 similarly secure the radial sealing members 38 thereto. The radial sealing members being comprised of a thin strip of resilient material flexibly wipe against their respective end plates 40 and 42 to preclude fluid therebetween and thus maintain the flow of fluid in the predetermined channels of the rotor.

40 The horizontal arm of each bracket 30 is positioned closely adjacent end plate 40 at the lower end of the rotor and at such a distance from the upper end plate 42 that the upper and lower layers of rotor element 36 are both supported closely adjacent their respective end plates. When constructed according to this arrangement, cleaning fluid being projected outward from the cleaning nozzles 26 to the adjacent blocks of

45 rotor element arrives at the surface thereof with substantially the same energy with which it was exhausted from the nozzle 26.

50 The radial outer portion of each element block 36 is provided with an arcuate filler plate 46 that is integrally secured thereto and is adapted to slidably abut the annular leaf 48 that is secured to the rotor shell 52 by brackets 54. The same brackets 54 that secure the annular leaf 48 to the rotor shell 52 also hold the flexible leaves which comprise the circumferential sealing means 58. The brackets 54 shown are securely held to the rotor shell by a bolt 56 which may be adjusted to

permit manual manipulation of the sealing members and an optimum sealing arrangement with their cooperating sealing members.

While this invention has been described with reference to the arrangement illustrated in the drawing, it is evident that various changes may be made without departing from the spirit of the invention, and it is intended that all matter contained in the above description or shown in the accompanying drawing shall be interpreted as illustrated only and limited only as defined in the following claims.

I claim:

1. A rotary regenerative heat exchanger apparatus having a rotor including a therefrom (adapted) rotor post and a concentric rotor shell joined by radial partitions to provide a series of sectional compartments therebetween, a housing surrounding said rotor having spaced inlet and outlet ports that

permit the supply and discharge of a heating fluid and a fluid to be heated, means rotating the rotor about its axis within the housing, spaced layers of "laminar" heat exchange element at axially opposite ends of each compartment adapted to absorb heat from the heating fluid and impart absorbed heat to the fluid to be heated, a source of cleaning fluid, nozzles at opposite ends of the rotor adapted to project a cleaning fluid on to the element adjacent thereto, and brackets secured to opposite ends of the radial partitions extending axially outward therefrom, (adapted) to support the heat exchanger element whereby the surface of the element confronting the rotor housing and the cleaning nozzle lies outward from the end of the rotor and thus is more closely adjacent to the cleaning nozzle.
